END CAP FOR A STADIUM SEAT

Wilmer R. Schultz, 1540 Chestnut St.,
Emmaus, Pa. 18049

Filed Apr. 1, 1974, Ser. No. 456,634

Term of patent 14 years

Int. Cl. D6—06

U.S. CL. D6—191

FIG. 1

FIG. 2

FIG. 3

FIG.
4

FIG. 5

FIG. 6

FIG. 1 is a perspective view looking toward the exposed side of an end cap for a stadium seat and showing my new design;

FIG. 2 is a perspective view of the reverse or underneath side of the end cap for a stadium seat illustrated in FIG. 1;

FIG. 3 is a top plan view of the end cap for a stadium seat;

FIG. 4 is a side view of the end cap for a stadium seat;

FIG. 5 is a front view of the end cap for a stadium seat, the rear view being a mirror image having substantially the same appearance; and

FIG. 6 is a cross-sectional view taken along line 6—6 of FIG. 4.

I claim:

The ornamental design for an end cap for a stadium seat, as shown and described.
